BLENDER

Frank J. Di Sesa, Lombard, Ill., assignor to Sunbeam Corporation, Chicago, Ill., a corporation of Illinois

Filed July 12, 1965, Ser. No. 86,109

Term of patent 14 years

(Cl. D89—1)

FIG. 1 is a perspective view of a blender embodying my new design;

FIG. 2 is a front elevational view thereof;

FIG. 3 is a side elevational view thereof; and

FIG. 4 is a top plan view thereof.

The dominant features of my design reside in those portions shown in solid lines.

I claim:

The ornamental design for a blender, as shown and described.
